UNITED STATES PATENT OFFICE.

HERMAN C. TALBOT, OF CHICAGO, ILLINOIS.

PAPER-DISPENSING DEVICE.

Application filed June 24, 1920. Serial No. 391,399.

To all whom it may concern:

Be it known that I, HERMAN C. TALBOT, a citizen of the United States, residing at Chicago, county of Cook, and State of Illinois, have invented new and useful Improvements in Paper-Dispensing Devices, of which the following is a specification.

The invention relates to paper dispensing devices, and particularly to manually or 10 coin-controlled devices of this character.

It is an object of the invention to provide, in conjunction with a swinging door and its actuating means, a separator which is adapted to separate one paper from the stack and 15 to prevent the discharge of succeeding papers.

It is a further object to provide a pin and slot connection between the separator and swinging door, whereby the separator may 20 be moved independently of the door for separating a paper from the stack, and thereafter the door may be swung into open position for the discharge of a paper thus separated.

25 A still further object consists in providing means to prevent movement of the separator beyond a predetermined extent, but permitting movement of the door.

With these and other objects in view, 30 which will become apparent as the description proceeds, a preferred embodiment of the invention is illustrated in the appended drawings, described in the specification and particularly pointed out in the claims annexed thereto.

In the drawings:

Fig. 1 is a front view of the device constructed in accordance with the invention, parts being broken away to disclose interior 40 arrangement.

Fig. 2 is a section on line 2—2 of Fig. 1.

Fig. 3 is a perspective view of the complete device.

Fig. 4 is a fragmentary side view of the 45 device showing the separator in position previous to discharge of a paper.

Fig. 5 discloses a fragmentary view with the parts in position that they take when the paper is being delivered.

50 Referring to the several views of the drawings, 1 designates generally a box of convenient form and of a size adapted to receive a stack of papers. The box comprises a top 2, a rear wall 3, a front wall 4 and side walls 5 and 6. As indicated in Fig. 2, the box is provided with a false

bottom, comprising a narrow strip 7 arranged in slightly slanting position, and a comparatively wide plate 8 which is arranged at a greater slant than the strip 7. 60 An adjustable partition wall 9 parallel to the front and rear walls of the box serves as a back rest for a stack of papers introduced into the box, in a manner hereinafter described. 65

The front wall of the device comprises a glass panel door 10 at the upper end thereof which is secured by hinges 11 to a transverse strip 12, constituting a portion of the front wall. A lock 13 serves to secure the panel door 10 in locked condition and when re- 70 moved the panel may be swung open for the purpose of introducing a stack of papers, as will be readily understood. The hinges 11 may be provided with springs in order to automatically maintain the panel door 10 in closed position, but such springs may be dispensed with, if desired, without affecting the present invention. The strip 12 of the front wall is provided at its lower edge with spring 75 controlled hinges 14, to secure thereto a trap door 15 which may be swung about the pintles of the hinges 14 to uncover the opening for which the door 15 constitutes a closure. Un- 80

derneath the door 15 a plate 16 is provided, which is adapted to slide in guides 17 arranged on the side walls of the box, the plate 16 ordinarily maintaining a distance from the lower edge of the door 15 for a purpose presently to be described. The slide plate 85

16 is connected at its ends by a link 18, articulated with the plate 16, as by 19, and pivotally secured to the door 15 by a headed pin 20 which extends through a slot 21 in the link 18. The link 18 extends beyond the 90

pivotal connection 20 of the door and is articulated with a member 22, which at its other end has a plurality of apertures 23, so that the adjacent end of an actuating lever 24 may be adjustably secured thereto. The 95

lever 24 is secured to the side wall by a pivot pin 25 and its free end may be moved, until such movement is arrested by an abutment pin 26, as is obvious from Fig. 3. A spring 27 secured to the side wall 6 and to the operative end of the lever 24 tends to maintain the latter out of engagement with the pin 26. 100

As indicated in Fig. 3, the side walls are formed with rectangular cut-outs 28 to provide for the passage of a transversely extending rod 29, which is formed with forwardly bent ends 30, pivotally secured at 105

31

2
to the lower ends of the links 18. To each side wall of the box a lever 32 is pivotally secured as at 33 and a connecting rod 29 extends through said levers to simultaneously 5 actuate the same as hereinafter will appear.

Assuming that the box has been filled with a stack of papers 34 and the discharge of a single paper is intended, the lever 24 is turned about its pivot 25 which movement 10 is, of course, imparted to the member 22, so that the link 18, by the operation of the member 22, will be raised and therewith the plate 16 will execute a vertical movement until the lower end of the slot 21 enters into 15 engagement with the pivot pin 20. In this position which is indicated in Fig. 4, the plate 16 has been lifted to such an extent that its upper edge is a little above the level of the lower edge of the paper to be discharged 20 whereby the outermost paper, being separated from the stack, is ready to fall out from the box by gravity. The lever 24 is further rotated whereby the link 18 is caused to rotate about its pivot 20 which entails a 25 continued opening of trap door 15 and a lifting of the slide plate 16. The lower portion of the link 18, rotating in counter-clockwise direction, will displace the ends 30 of the connecting rod toward the right, as shown in Fig. 5, until the links 32 engage the right-hand side of the cut-outs 28 and are stopped from further movement. At this point the sliding plate 16 has reached a 30 position between the foremost paper and the stack whereby outward movement of the stack is effectively prevented. The continued movement of the lever 24 until it reaches the abutment pin 26, will cause the link 18 to turn about its pivot 19, and consequently, 35 will effect the complete opening movement of the door 15 such that the separated paper may now slide out through the opening, normally closed by the door 15. The clockwise rotation of the lever 24 places the 40 spring 27 under tension and as soon as the pressure acting on the lever is removed, the spring will automatically restore the lever to normal position, as indicated in Fig. 3.

While the drawings disclose a preferred 50 mode of the invention, various changes and alterations can be made without departing from the spirit of the invention. I do not intend, therefore, to limit myself to details of construction, as shown, but want to include all changes, alterations and modifications 55 constituting departures within the scope of the invention as defined in the appended claims.

I claim:

60 1. In a paper dispensing device, a swinging door, a vertically reciprocating plate arranged underneath said door, a pin and slot connection between said plate and door, and means acting on said connection for raising

said plate and subsequently opening said door.

2. In a paper dispensing device, a swinging door, a vertically reciprocating plate arranged underneath said door, a link pivotally connected to said plate and door, and means for actuating said link to raise said plate sufficiently to separate one paper from the stack and hold the stack against movement, and to subsequently open the door for the discharge of the separated paper. 75

3. In a paper dispensing device, a swinging door, a vertically reciprocating plate arranged underneath said door, a link pivotally connected to said plate and having a pin and slot connection with said door, and means for actuating said link whereby said plate is raised and subsequently the door is opened. 80

4. In a paper dispensing device, a swinging door, a vertically reciprocating plate arranged underneath said door, a link pivotally secured to said plate having a pin and slot connection with said door, and means for actuating said link to be raised and subsequently turned about different pivots 90 whereby said plate is raised and then the door opened. 85

5. In a paper dispensing device, a swinging door, a vertically reciprocating plate arranged underneath said door, a link pivotally secured to said plate and having a pin and slot connection with said door, means for actuating said link to be raised and subsequently turned about different pivots 95 whereby said plate is raised and then the doors opened, and means for limiting the vertical movement of said plate. 100

6. In a paper dispensing device, a swinging door, a vertically reciprocating plate arranged underneath said door, a link pivotally secured to said plate and having a pin and slot connection with said door, an actuating lever, a member pivotally connected to said lever and articulated with an extended portion of said link, and means for limiting the vertical movement of said plate. 105 110

7. In a dispensing apparatus, in combination, a container having an outlet, a door hinged on one side of said outlet to normally partially close the same, a slidable member defining a side of said opening opposite to said door, and adapted to normally, and when the door is closed, directly engage the door for forming a complete closure for the opening and means connecting said door and sliding member for operating them in succession. 115 120

In testimony whereof, I have affixed my signature in the presence of two witnesses.

HERMAN C. TALBOT.
